AMPLIFIER

Clarence W. Hansell, Port Jefferson, N. Y., assignor to Radio Corporation of America, a corporation of Delaware

Application May 27, 1931, Serial No. 540,311

3 Claims. (Cl. 179—171.5)

This invention has as its principal object, the provision of methods and means for the elimination of distortion in electron discharge device amplifiers and especially the distortion due to the drooping of a characteristic curve of the amplifier caused by grid rectification.

A linear characteristic for the output of an electron discharge device amplifier relative to its input may readily be obtained when the output of the amplifier is kept within approximately half of its commercial continuous wave rating. However, beyond that point, the ratio of output to input for the amplifier is no longer a constant due to the characteristic curve of the amplifier which drops beyond the half rating valve. In the case of telephonic communication or multiplex communication, this distortion limits a transmitter output to approximately half of its rated output, making a great reduction in power and transmitter efficiency as well as increasing cost of construction and operating expenses for transmission of signals of desired power.

The drooping characteristic of an amplifier may be attributed to several causes, the most important of which and by far the most influential factor in causing the droop is that of grid rectification.

Relative to other causes of distortion, such as saturation of vacuum tubes used for an amplifier, grid rectification presents a difficult problem inasmuch as it causes an abrupt break in the characteristic amplifier curve of the amplifier. That is, in the case of saturation, the saturation characteristic of tubes is fairly continuous and can be balanced out to a great extent and practically sufficiently, by adjusting earlier amplifier stages so that they produce a curvature opposite to the saturation curvature to be corrected.

Heretofore, in order to reduce the effect of grid rectification, the input circuit of the amplifier has been artificially loaded with resistances so that the increased losses produced by the grid rectification are small in comparison with the losses throughout the loaded input circuit. Consequently, the change in effective grid resistance, due to rectification, has a relatively small effect upon the voltage regulation of the input circuit and, therefore, upon the curvature of the amplifier characteristic.

But such a loading method, in order to be practically effective, necessitates a large ratio between radio frequency losses in the input or grid excitation circuit relative to the grid losses, entailing a marked reduction in power, efficiency, and amplification in the stage of the amplifier.

As a result of this, for a given output, an increased number of stages are needed having concomitant thereto, disadvantages of increased construction and operating costs to say nothing of increased unreliability of an installation.

5

To overcome the foregoing disadvantages is a further object of the present invention and in the accomplishment thereof, according to the present invention, the input or grid circuit of an amplifier is uniformly loaded up to a point where grid rectification occurs with its consequent increase in loading, and beyond that point this loading is rapidly decreased whereby the total load on the input circuit remains constant, or may even decrease so that the input voltages are built up more rapidly on the grids or control electrodes of an amplifier or amplifiers, after grid rectification occurs than was the case before my invention was applied.

15

To accomplish such a variation in threaded loading, it is a further object of the present invention to provide an electron discharge device load for the grid circuit of an amplifier, the electron discharge device or devices forming part of the load being adjusted so that cut off occurs beyond the point where grid rectification occurs in the amplifier. In other words, according to the present invention, the amplifier input circuit is loaded with vacuum tubes instead of fixed resistances, the tubes being so adjusted that their effective anode resistance or impedance will increase with increasing amplitude of radio frequency voltage in such a manner as to cause a correction of the non-linear amplitude characteristic of the electron discharge device amplifier.

20

Although it has been attempted to define the present invention in the appended claims, it, of course, may best be understood by referring to the accompanying drawings, given solely by way of illustration, wherein;

25

Figure 1 illustrates a characteristic curve for a 50 kw. amplifier.

30

Figure 2 illustrates a transmitter utilizing an amplifier having a characteristic such as shown in Figure 1 and having means for correcting curvature of the amplifier characteristic.

35

Figures 3 and 4 are curves explanatory of the curve correction method and means of the present invention, and,

40

Figure 5 illustrates a modification of the invention shown in Figure 2.

45

Fig. 6 illustrates a further modification of the invention shown in Fig. 2.

50

Turning to Figure 1, there is graphically illus-

trated by the solid line 2, the relationship between the voltage or current output of a 50 kw. commercial amplifier and its input or grid voltage. It will be noticed that at point 4, or at approximately half of the maximum output power of which the amplifier is capable, the curve begins to droop and is no longer a straight line such as it is between point 4 and the zero point of the curve. For distortionless full rating output it is desired that the characteristic curve continue in a straight line as indicated by the dotted portion 6.

To give the amplifier A of Figure 2, which normally has the drooping characteristic shown in Figure 1, the desired linear characteristic beyond the point where grid rectification occurs, the amplifier A, comprising pushpull connected electron discharge devices 8, 10, having a tunable input circuit 12 and a tunable output circuit 14 together with means comprising neutralizing condensers 16, 18 for preventing the effects of inter-electrode feed back, has coupled to its input circuit, as loading therefor, electron discharge devices 20, 22.

The latter have their anodes 23 coupled to the input circuit 12 of amplifier A through current limiting resistances 24 and blocking condensers 32 which, in addition, serially connects the anodes 32 for high frequency currents. The grids of the loading tubes 20, 22 are polarized from a suitable source of potential (not shown) through lead 34 and they are grounded for radio frequency potentials by means of by-passing condensers 36 in series and parallel with which may be resistances (not shown) for suppressing parasitic oscillations in the loading tubes.

The anodes and grids of the loading tubes 20, 22 are undidirectionally polarized so that on negative half cycles of radio frequency potentials, derived from the input circuit 12 of amplifier A and applied to the anodes of the loading tubes, exceeding the peak potential before which grid rectification occurs, the tubes 20, 22 cut off. That is, there is cessation of current flow in the loading tubes 20, 22 during a negative portion of each cycle after a certain value of radio frequency potential is exceeded which results in an increase in impedance of the loading tubes as the input to amplifier A goes beyond the point where grid rectification occurs and the effective grid resistance decreases.

That is, referring to Figure 3, which indicates graphically the relation between the anode current flow in a particular type of loading tubes and the applied instantaneous anode radio frequency voltages between zero and 900 volts, the anode current through the loading tubes relative to the applied radio frequency potential is substantially a constant or in other words, the characteristic of the loading tubes up to 900 volts corresponding to point 4 of Figure 1 is almost a straight line, thereby loading the input circuit 12 uniformly or with an equivalent resistance of a constant value. However, beyond 900 volts, which, as already indicated, corresponds to point 4 of Figure 1 where grid rectification occurs in the amplifier A, cut off occurs in the loading tubes 20, 22 during a portion of the cycle of alternating current anode voltage, as a result of which their effective alternating current impedance or re-

sistance increases thereby causing a discontinuous decrease in the loading of the input circuit 12 of amplifier A of the same character as the increase in loading by starting of grid rectification in the amplifier.

This decrease in loading of the input circuit of amplifier A causes voltages to be built up in the input circuit at a much faster rate after grid rectification occurs than would be the case if loading by fixed resistances were used. Consequently, by virtue of this increased speed of building up of potentials on the input electrodes of amplifier A, the characteristic curve of amplifier A will no longer droop but will continue on the straight dotted line 6 of Figure 1 thereby prolonging desired linear characteristic up to a point much nearer the maximum possible power output from the amplifier.

Customarily, the voltage applied to the amplifier grids of amplifier A is a modulated voltage, derived from constant frequency carrier energy from source 1 combined with amplified modulating or audio potentials from source 3 in a modulator and radio frequency amplifier 5. The current which will flow through the anode circuits of the correcting tubes 20, 22 is graphically illustrated in Figure 4, the shaded areas representing the current cut off by the correcting vacuum tubes. This decrease in current corresponds to the power made available for correcting the characteristic of amplifier A.

A modification of the present invention is illustrated in Figure 5 wherein the pushpull amplifier A is of the screen grid type, the screen grids being biased through a suitable resistance 40 connected to the plate potential lead. The screen grids, of course, prevent the effects of interelectrode feed back.

To increase the cut off effect of anode potentials on loading tubes 20, 22, a rectifier 31 is coupled to the input circuit 12 here shown inductively coupled thereto. The rectified current is applied to a resistor 33 in the grid polarizing lead 34 so that the added potential engendered in resistance 33 is sufficient, at the time of grid rectification occurs in amplifier A to cause the beginning of a decrease in the proportionality of the radio frequency current absorbed by the tubes 20 and 22. This proportionality continues to decrease, as the input to the amplifier increases, in a manner to correct the objectionable drooping amplitude characteristic of the amplifier.

Of course, if desired the rectification may be produced in the grids of tubes 20, 22 without using the separate rectifier 31, by feeding radio frequency energy to the grids of tubes 20, 22 of the same polarity as their anode voltages and at the same time using a combination of fixed bias from a negative source and grid leak bias obtained by passing rectified grid current through a resistance. Figure 6 illustrates one method for doing this wherein the grids of tubes 20, 22 are connected together by a grid leak resistance 200, and supplied, in addition to the supply through the interelectrode capacities of the tubes, with high frequency currents through condensers 36a. Condensers 36 act as by passing condensers for the alternating component of the rectified current.

Having thus described my invention, what I claim is:

1. In a system for the amplification of undulatory electrical currents, an amplifier comprising a pair of pushpull connected electron discharge

devices having an input circuit and an output circuit, electron discharge devices coupled to the input circuit of said amplifier acting as a load therefor, and means for polarizing electrodes of the devices forming the load whereby when said 5 amplifier characteristic begins to droop, the load- 10 ing electron discharge devices are cut off thereby allowing input potentials to increase at a faster rate on the input electrodes of said electron discharge device amplifier.

2. In a system for the amplification of undulatory electrical currents such that the ratio of the 15 amplified currents to the currents to be amplified remains constant over a wide range of values for input currents, the combination of a pair of 20 electron discharge devices connected in pushpull fashion for amplifying the undulatory currents, an electron discharge device load coupled to the input circuit of the pushpull connected electron discharge device amplifier, and means for polarizing electrodes of said load electron discharge devices so as to alter their conductivity in such a

way as to correct the characteristic of the pushpull connected electron discharge device amplifier so that the ratio of its output to its input, for high values of input, remains constant over a desired predetermined range of values for input currents supplied to said pushpull connected 5 electron discharge device amplifier.

3. In combination, an amplifying system comprising a pair of pushpull electron discharge devices each having an anode a cathode and a control electrode, means for preventing oscillation generation in said devices, an input circuit connected across the control electrodes of said devices, a pair of load electron discharge devices coupled to said input circuit, means for simultaneously energizing said input circuit and said load devices from a source of energy to be amplified, and means, responsive to high values of energy of said source to cause rapid increase in 10 impedance of said load discharge devices. 15 20
